Primary Examiner — Dana K Weiland*Assistant Examiner* — Kathryn Elizabeth Zieno(74) *Attorney, Agent, or Firm* — Justin Lampel(57) **CLAIM**

The ornamental design for a toilet seat for children as shown and described.

DESCRIPTION

FIG. 1 is a perspective view of a toilet seat for children showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of area 9 shown in FIG. 1; and, FIG. 10 is an enlarged view of area 10 shown in FIG. 1.

The evenly-spaced broken lines show portions of the toilet seat for children that form no part of the claimed design; the dash-dot-dash broken lines indicate the cutoff boundaries for enlarged detail portion views and form no part of the claim.

1 Claim, 10 Drawing Sheets(56)
